UNITED STATES PATENT OFFICE

96,902

DESIGN FOR A TEXTILE FABRIC OR SIMILAR ARTICLE OF MANUFACTURE

Emmanuel M. Cohen and Jesse Olenick,
New York, N. Y.

Application August 9, 1935, Serial No. 58,059

Term of patent 3½ years

To all whom it may concern:

Be it known that we, Emmanuel M. Cohen and Jesse Olenick, both citizens of the United States and residents of New York (Borough of Manhattan), in the county and State of New York, have invented a new, original, and ornamental Design for a Textile Fabric or Similar Article of Manufacture, of which the following is a specification, reference being had to the accompanying drawing, forming part thereof.

The figure of the drawing is a plan view of a piece of textile fabric embodying our new design, a repeat unit of which is outlined on the drawing by dot and dash lines.

We claim:

The ornamental design for a textile fabric or similar article of manufacture as shown and described.

EMMANUEL M. COHEN.
JESSE OLENICK.
